FLEXIBLE WALL STRUCTURE

James J. Skelly, Cleveland Heights, Ohio

Application July 14, 1944, Serial No. 544,909

10 Claims. (Cl. 160—229)

1

My invention relates to structures particularly useful where greater rigidity is desired in one dimension than in another.

An object of my invention is to provide a construction and a method of assembly for a sheet, wall, or other structural element which is relatively rigid with respect to one dimension and relatively flexible with respect to a transverse dimension in a plane, or which may be warped into various shapes while retaining stiff straight-line elements. Another object is to provide a structure which is light in relation to its area and in relation to its strength, which is readily fabricated and is adapted to ornamentation or to the use of ornamental finishes.

Another object is to provide an improved disappearing door or panel.

A further object is to provide an embodiment adapted equally well to bending in reverse directions and capable of having the same appearance on opposite sides.

Still another object of my invention is to provide space-saving closures for rooms, cabinet, garages, and the like.

Another object is to provide an improved construction for light duty conveyor belts, window shutters, blinds, panels, or the like which must be flexible yet watertight.

Other and further objects, features and advantages of the invention will become apparent as the description proceeds.

In accordance with a preferred form of my invention, channel members or channel-shaped slats, and strips of resilient material such as natural or synthetic rubber or rubber-like material are fitted in interlocking relation or bonded. The slats may be composed of sheet-metal, plastic material, perforated metal, screening or other suitable material according to the purpose intended.

A better understanding of the invention will be afforded by the following detailed description considered in connection with the accompanying drawing and those features of the invention which are believed to be novel and patentable will be pointed out in the claims appended hereto.

In the drawing:

Fig. 1 is a cross-section view of a structure forming one embodiment of my invention.

Figs. 2 and 3 are cross-section views of interlocked structures in accordance with my invention.

Fig. 4 is a diagram illustrating the manner of clinching the assembly illustrated in Fig. 3.

Fig. 5 is a cross-section view of a reversible

2

structure presenting ornamental appearance on both sides.

Fig. 6 is a longitudinal section view of the structure of Fig. 5 represented as cut by a plane 6—6.

Fig. 7 is a cross-section view of a cabinet employing an overhead disappearing door or front panel in accordance with my invention, and,

Fig. 8 is a view of a flexible screen constructed in accordance with my invention.

10 Like reference characters are utilized throughout the drawing to designate like parts.

As illustrated in Fig. 1, a plurality of relatively stiff pieces 11 are arranged side by side alternating with strips 12 of flexible, preferably

15 resilient material. As indicated by the cross-sectional shapes shown in Fig. 1, the elements 11 and 12 are both channel-shaped or formed with flat U shaped cross-section and are interconnected to provide tensile strength in a direction transverse to the length of the elements 11 and 12. As shown, the pieces 11 have edge portions 13 making right-angle bends with the web portion 14. The bent edges 13 overhang corresponding portions 15 of the resilient strips 12. In addition 20 the contacting surface of the elements 11 and 12 are cemented together.

Where an impervious wall or panel is desired the pieces 11 may be composed of sheet metal, transparent plastic, or the like, which lend themselves to decorative finishes or color effects. Owing to the channel shape, stiffness is obtained 25 with respect to the dimension parallel to the elements 11 and 12, while preserving lightness of construction. On the other hand flexibility is

30 provided with respect to the dimension perpendicular to the elements 11 and 12. This permits the structure to be bent into the form of a circular cylinder or an irregular cylinder, or to be warped into a warped plane, or other shape containing straight line elements.

The strips 12 may be composed of natural or synthetic rubber or rubber-like material such as represented, for example, by Neoprene, Koroseal, Thiokol, Vinylite and the like.

35 According to the effect desired, the pieces 11 may also be composed of transparent plastic, such as certain synthetic resins or condensation products, or they may be composed of perforated metal or screening.

40 Rubber cement of the rubber-to-metal type may be employed for bonding the strips 12 to the pieces 11. For example, I may use a cement of the type sold by the B. F. Goodrich Company, under the name "Vulcalock." Preferably care is taken to obtain intimate contact between the cemented

surfaces when the cement is applied, and a tight bond may be assured by the application of pressure when the union is made.

For interlocking the members 11 and 12, the channel members 11 may be formed so that their cross-sections have reentrant portions 16 fitting corresponding grooves in the resilient strips 12, as shown in Fig. 2.

For providing additional strength in the union between the strips 12 and the channel member 11, the re-entrant portions 16 of the members 11 may be bent back toward the web portions 14 to put a portion of the rubber under pressure and to clinch the joint.

For producing the clinched joint shown in Fig. 3, a suitable tool comprising mating dies 17 and 18 may be employed as shown in Fig. 4. If the assembled strip in the form shown in Fig. 2 is placed between the dies 17 and 18 and the dies are moved towards each other and released, the re-entrant portions 16 will be bent down or clinched as shown.

Since the rubber strips are joined to the metal or plastic channel members in intimate contact, a structure is provided which is completely impervious to water although highly flexible with respect to one dimension. The stiffness in the other dimension provides obvious advantages when using the structure for conveyor belts, window shutters, blinds or disappearing panels, or the like.

If the same appearance or finish is desired on both sides a double set of channel members may be provided. For example, as illustrated in Fig. 5, pairs of channels 11 such as those of Fig. 1 may be employed with resilient strips 12' of modified form, shown as having I-shaped cross-section. The I-strips have the base portions 19 of the I locked between pairs of channels 11 within the bent edges thereof. Preferably the I-strips also have relatively wide webs 21 to provide full flexibility of the structure in either direction and to permit accordion folding, if desired.

The portion 19 of the strip 12' may be bonded to the inner surfaces of the corners of the channels 11 by applying rubber cement to the surface and pressing the cemented surfaces together. This may be done by inserting an expandable mandrel between a pair of opposite channels arranged to compress the rubber portions 19, and removing the mandrel after the bond has been made. However, bonding of the strips 12' to the channels 11 is unnecessary if means are provided for holding the channels of each pair together. For example, blocks 22 may be inserted at intervals within each pair of channels 11 and the bonding of such blocks to the inner surface of the channels is a relatively simple operation as pressure may very readily be applied. The blocks 22 may be composed of rubber or other suitable materials.

Although the flexible structure described is by no means limited to certain uses which have been indicated by way of example, one of these uses has been shown in Fig. 7 for the sake of illustration. In this case a cabinet 23, shown in vertical cross-section, has a front opening 24, the edges of which are formed by a casement adapted to receive a flexible sliding panel 25 for closing the opening 24.

The casement includes grooves 26 at each end for slidably retaining and guiding the ends of slats 11 of structures such as shown in Figs. 1, 2, 3, or 5. For opening the cabinet 23 suitable

means are provided for withdrawing the panel 25 and bending it out of the plane of the opening 24, preferably into a disappearing position.

For example, a knob or handle 27 may be provided for sliding the flexible panel 25 upward. Suitable means such as a drum or the like may be provided for causing the panel to follow a bend 28 and may be used for winding up the panel when the handle 27 is raised. However, my invention is not limited thereto. In the arrangement illustrated the groove 26 is continued along the portion 26' at the top and back of the cabinet 23 for causing the panel 25 to bend out of the plane of the opening 24 when the handle 27 is raised.

The type of structure thus far described is especially useful where watertight flexible walls are desired. However, it may also be employed for flexible open lattice-work or screening as illustrated in Fig. 8, where spaced slats 11, as previously described, are employed in conjunction with resilient strips 29 which are relatively short instead of running the length of the slats 11. The cross-sectional shapes of the elements 11 and 29 may correspond to those of the elements 11 and 12 or 11 and 12' shown in Figs. 1-5.

I have herein shown and particularly described certain embodiments of my invention and certain methods of operation embraced therein for the purpose of explaining its principle of operation and showing its application, but it will be obvious to those skilled in the art that many modifications and variations are possible and I aim, therefore, to cover all such modifications and variations as fall within the scope of my invention which is defined in the appended claims.

What I claim as new and desire to secure by Letters Patent of the United States, is:

1. A flexible structural element comprising a plurality of relatively rigid strips, and a plurality of strips of resilient material joining successive relatively rigid strips and bonded thereto.
2. A flexible wall comprising a plurality of relatively rigid channel members arranged side by side and a plurality of strips of resilient material inter-leaved with successive channel members and bonded thereto.
3. In combination a plurality of channel members with re-entrant cross-sections and a plurality of strips of flexible material, each interlocked with a pair of channel members by the re-entrant sections to form a sheet relatively rigid in one direction and flexible in another.
4. The combination of claim 3 in which the strips are under compressive strain in the re-entrant portion of the channel members whereby the re-entrant portions are in binding relation with the flexible strips.
5. In combination a plurality of strips of resilient material with substantially I-shaped cross-section, and a plurality of pairs of channel members with substantially flat U-shaped cross-section, each I-shaped strip having a pair of base portions, each of which is enclosed by a pair of said channel members to lock the resilient strips and channel members together.

6. The combination of claim 5 in which blocks fitted into said channel members at intervals therealong and cemented to inner surfaces thereof are secure said members together.

7. A flexible screen comprising a plurality of relatively rigid channel members arranged successively side by side and a plurality of strips of resilient material, short in length compared

with the channel members, placed at intervals between pairs of channel members and connected thereto for resiliently joining them and spacing successive channel members apart.

8. A method of forming a flexible wall which comprises forming channel members with substantially re-entrant C-sections, moulding resilient strips to interfit said C-section members, interleaving said members and strips in alternating succession, and bending the re-entrant portion of the channel members to compress the adjacent portions of the resilient members to bind them in place.

9. In combination a plurality of strips of re-

silient material with a cross-section, the outline of which comprises a pair of base portions joined by a web portion, and a plurality of pairs of bent shapes with flanges, each of said strips having each of its base portions enclosed between a pair of said bent shapes, each flange overlapping the base portion of the resilient strip to lock the resilient strips and bent shapes together.

10. The combination of claim 9 in which fastening elements are fitted into said bent shapes at intervals therealong and fastened thereto to secure said bent shapes together.

JAMES J. SKELLY.
